UNITED STATES PATENT OFFICE.

JOHN P. GOLDEN, OF COLUMBUS, GEORGIA, ASSIGNOR TO GOLDEN'S FOUNDRY & MACHINE CO., OF COLUMBUS, GEORGIA.

SHAFT MOUNTING.

Application filed March 19, 1924. Serial No. 700,297.

To all whom it may concern:

Be it known that I, JOHN P. GOLDEN, a citizen of the United States, and resident of Columbus, in the county of Muscogee and State of Georgia, have invented certain new and useful Improvements in Shaft Mountings; and I do hereby declare the following to be a full, clear, and exact description of the invention, such as will enable others skilled in the art to which it appertains to make and use the same.

This invention relates to improvements in shaft mountings and has particular reference to means for providing mountings for a shaft in hangers or in a pillow-block structure,—one object of the invention being to provide simple and efficient means to adjustably support the bearing box in a hanger or pillow-block structure in a manner to avoid the use and consequent objections of set screws.

A further object is to so construct and arrange bearing-box mounting means that said bearing box shall be firmly held at any desired position of vertical adjustment and so that it may have horizontal adjusting movement.

With these and other objects in view, the invention consists in certain novel features of construction and combinations of parts as hereinafter set forth and pointed out in the claims.

In the accompanying drawings,—

Figure 1 is a view illustrating an embodiment of the invention.

Figure 2 is a view in plan.

Figure 3 is a view at right angles to Figure 1.

Figures 4 to 7 inclusive, are views illustrating modifications, and

Figures 8 and 9 show an application of my improvements in a pillow-block structure.

In the embodiment of the invention shown in Figures 1 to 3, a hanger is represented at 1 and constructed with depending arms 2 connected at their lower ends by a yoke 3 and between the hanger arms, a bearing box 4 is shown.

The bearing box 4 is provided at diametrically opposite sides with lugs or enlargements 5 having flat taper faces 6 and the upper ends of these lugs or enlargements may be provided with sockets 7 adapted for the reception of screws as here-

inafter more fully explained. The inner faces of the hanger arms 2 are made vertical and are curved somewhat transversely. Between the transversely curved vertical inner faces of the hanger arms and the flat taper faces of the lugs or enlargements 5, wedges 8 are disposed,—each wedge having a vertical transversely curved outer face to engage a similarly shaped face of the adjacent hanger arm and the inner face of each wedge is made flat and tapering vertically. By inserting the wedges between the bearing box and the adjacent hanger arms when the bearing box shall have been adjusted vertically (which may be accomplished by a screw device 9), a slight tapping on the upper ends of the wedges will serve to tighten the same and the bearing box will be firmly held against vertical displacement. With the use of my improvements, I obviate the objectionable features incident to the slipping of set screws heretofore employed and the strains or pulls of pulley belts will be effectually met.

In order to guard against any possibility of vertical displacement of the wedges, I may provide them with inwardly projecting arms 10 which are perforated for the passage of bolts 11 which latter enter the sockets 7 in the lugs 5 on the bearing box and said bolts may be provided at their upper end portions with nuts 12 which seat against the horizontal upper ends 13 of said lugs.

While my improvements will effectually hold the bearing box in any desired position of vertical adjustment still, by reason of the curved co-acting faces of the wedges and hanger arms, slight horizontal adjusting movements of the bearing box will be permitted.

In the embodiment of the invention shown in Figures 4 and 5, the inner faces of the hanger arms 2 are made flat and vertical while the outer faces of the lugs or enlargements 5 on the bearing box are made tapering and transversely curved as indicated at 14. In this embodiment of the invention, wedges 15 are employed having straight vertical outer faces to engage the hanger arms and flat taper faces 16 to engage the transversely curved taper faces 14 of the lugs or enlargements 5. The wedges 15 are each provided at respective side edges with outwardly projecting flanges 17 which embrace

portions of the hanger arms and prevent possibility of lateral displacement of said wedges.

The construction shown in Figures 6 and 5 7 differs from the construction shown in Figures 4 and 5 in that the wedges 18 are provided on their inner sides with transversely curved taper faces 19 to engage the similarly shaped faces on the lugs or enlargements 5 of the bearing box 4.

In Figures 8 and 9, I have shown my improvements as embodied in a pillow-block structure, in which a pillow-block frame is indicated at 20 and the vertical members of 15 the same are provided on their inner sides with vertical transversely curved faces 21, while the lugs or enlargements on the bearing box are made with flat taper faces 22. The wedges 23 disposed between the bearing 20 box and the upright members of the frame 20 are provided on their outer sides with vertical transversely curved faces 24 to engage the transversely curved faces 21 of said upright members and the inner sides of 25 said wedges are made with flat taper faces 25 to engage the flat taper faces 22 on the lugs or enlargements of the bearing box. In this form of construction, the wedges may be provided with inwardly projecting lugs, such as lugs shown at 10, Figure 1, for the 30 passage of bolts 11 which enter sockets 7 in the lugs or enlargements 5 of the bearing box, so that the parts may be securely held in position when once adjusted.

Having fully described my invention what I claim as new and desire to secure by Letters-Patent, is:

1. In a shaft mounting, the combination 40 with a stationary frame having diametrically opposite transversely curved vertical faces, and a bearing box within said frame and provided with diametrically opposite integral external taper faces, of wedges disposed between the taper faces of the bearing 45 box and the transversely curved faces of the frame, each wedge being free and independent of the other wedge.

2. In a shaft mounting, the combination of a stationary frame, a bearing box therein, one of said parts at each side of the bearing box having a transversely curved vertical face and the other part at each side of the bearing box having a taper flat face, the face on the bearing box defining an integral projection, and wedges disposed between and bearing against the faces of the bearing box and frame respectively, each being free and independent of the other wedge. 50 55

3. In a shaft mounting, the combination of a stationary frame having diametrically opposite transversely curved vertical faces, a bearing box provided at diametrically opposite sides with integral enlargements having taper faces, and wedges disposed between the taper faces on the bearing blocks 60 65 and the transversely curved vertical faces in the frame.

4. In a shaft mounting, the combination of a frame including parallel members, a bearing box between said members, said bearing box having integral enlargements at 70 respective sides, wedges disposed between said enlargements and the parallel members of the frame, said wedges having lateral projections, and bolts passing through said lateral projections and entering the enlargements on the bearing box. 75

5. In a shaft mounting, the combination of a frame including parallel members having their inner faces curved transversely, a bearing box disposed between said parallel members, said bearing box having integral enlargements provided with taper outer faces, wedges disposed between the taper faces of the enlargements on the bearing box and the transversely curved faces of the parallel members of the frame, said wedges having lateral projections disposed over said enlargements, and bolts passing through 80 85 said lateral projections and entering said 90 enlargements on the bearing box.

In testimony whereof, I have signed this specification.

JOHN P. GOLDEN.
